BREECH BOLT LOCK AND ACTUATOR
FOR FIREARMS

Howard R. Clarke, West Pembroke, Maine

Application September 15, 1948, Serial No. 49,433

10 Claims. (CL. 89—190)

1

My present invention relates to firearms and particularly to bolt action rifles whether manual, semi-automatic, or fully automatic in their operation.

Where a firearm is to use ammunition developing high breech pressures, it is necessary to provide means to lock the closed bolt securely to the receiver. This locking of the bolt has customarily been accomplished by providing the receiver and the bolt with locking lugs disposed to be in mutual engagement when the bolt is closed and partially rotated.

While a bolt locked in that manner is adapted to be safely operated, it is objectionable, particularly where automatic or semi-automatic operation is required because excessive power is needed to rotate the bolt due to the fact that the gas pressure forces the bolt lugs tightly against those of the receiver.

In accordance with my invention, I provide a firearm that has its receiver formed with a pair of transversely aligned pockets. The bolt, which is mounted in the receiver to reciprocate between closed and open positions, includes a bolt shell having locking arms pivotally connected to it to swing outwardly from an inoperative position in which the bolt shell is free to reciprocate into the pockets when the bolt is in its closed position. An actuator is slidable in the shell and includes a wedge portion engageable with the arms to establish a driving connection between the actuator and the bolt shell when the actuator is driven forwardly and to wedge the arms apart and into their pockets when the bolt shell is closed. I provide a shouldered member slidably connected to the bolt shell to move relative thereto into and out of a position in which, when the locking arms are operatively positioned, its shoulders engage the free ends of the arms to lock them positively against being forced into their inoperative position. The member is also slidably connected to the actuator to provide predetermined movement of the actuator in either direction before it is moved thereby.

By this construction, my bolt is securely locked to the receiver but may be easily unlocked by driving the member rearwardly so that its shoulders do not block movement of the locking arms into their inoperative position. This requires minimum power since the shoulders are subjected to only a portion of the pressure on the parts that is developed when the firearm is fired and the power employed to unlock the bolt is not added to increase the friction between the locking arms and the receiver. While the actu-

2

ator may be moved rearwardly by any means, I prefer that its rearward action be initiated automatically in response to gas pressure with the lag between the movement of the actuator and the movement of the member serving both to time the unlocking of the bolt so that residual pressures in the barrel may be safely employed to ensure the completion of the travel of the bolt into its open position and to time the locking of the bolt when fully closed by the actuator.

A firearm in accordance with my invention also has many other features relating to the ease of its assembly and disassembly and also to simple but reliable trigger controlled firing mechanism for use in semi-automatic or fully automatic operation.

In the accompanying drawings, I have shown embodiments of my invention which serve to illustrate these and other of its novel features and advantages. In the drawings:

Fig. 1 is a partly sectioned, fragmentary, side view of a firearm in accordance with my invention.

Fig. 2 is a horizontal section, on an enlarged scale, through the receiver of the firearm shown in Fig. 1.

Fig. 3 is a vertical section through the bolt.

Fig. 4 is a front end view of the bolt.

Fig. 5 is a section along the lines 5—5 of Fig. 1.

Fig. 6 is an exploded view showing the bolt parts in side view.

Fig. 7 is a bottom plan view of the bolt shell.

Figs. 8, 9, and 10 are sections, respectively along the lines 8—8, 9—9, and 10—10, of Fig. 1.

Fig. 11 is a fragmentary view of the slide.

Fig. 12 is a section through the charging handle showing the means by which it is detachably locked to the slide.

Fig. 13 is a fragmentary and partly sectioned view showing the support of the barrel between the fore stock and the hand guard.

Fig. 14 is a bottom plan view of the hand guard.

Fig. 15 is a section along the lines 15—15 of Fig. 13.

Fig. 16 is a partly sectioned view of the firing mechanism shown in Fig. 1 and equipped with means to render its operation fully automatic.

Fig. 17 is a section along the lines 17—17 of Fig. 16.

Fig. 18 is a fragmentary plan view of the control by which the firing mechanism is set for either semi-automatic or fully automatic operation, and

Fig. 19 is a section through the firing mechanism of Fig. 1 showing the safety.

In the embodiment of my invention shown in the drawings, I have indicated generally at 29 the receiver of a semi-automatic or automatic rifle. A chambered barrel 21 is threaded into the receiver 20 and both are supported in a 5 suitably inletted stock 22.

Within the receiver 20 is a bolt generally indicated at 23. The bolt 23 is reciprocable between the closed position shown in Fig. 1 in which it seats a cartridge 24 in the chamber of the barrel 21 and an open position in which it is rearwardly of the port 25 through which empty cartridge cases are ejected. Forward movement of the bolt 23 from its open position results in another cartridge 24 being picked up thereby from the magazine 26 and seated in the chamber of the barrel 21.

In accordance with my invention, I provide the receiver with one and preferably two cam pockets 27 which are shown as being transversely aligned. (See Fig. 2.)

My bolt consists of a bolt shell 28 having at its forward end a cartridge engaging, recessed face 29, an axial chamber 30 opening through its rear end, and a transverse slot 31 intersecting the chamber 30. A pair of locking arms, generally indicated at 32, are pivotally connected to the bolt shell 28. Preferably, the locking arms 32 are formed with integral, slightly tapered pintles 33 adapted to enter correspondingly tapered bores 34 intersecting the ends of the slot 31 at its front edges. Each locking arm 32 includes an outer cam portion 35 complementary in size and shape to the cam pockets 27 and has on its inner surface a contact portion 36 adjacent its pintle 33 and a ledge 37 adjacent its free end. The locking arms 32 are free to swing into a housed inner or inoperative position in the ends of the slot 31 in which they do not interfere with the reciprocation of the bolt shell 28 or outwardly into an operative position into the cam pockets 27. The locking arms 32 are so located that when their cam portions 35 are in the pockets 27, the bolt shell 28 is in its closed position.

My bolt also includes an actuator generally indicated at 38 and having a flange 39 engageable with the rear end of the bolt shell 28 and a portion 40 extending into the bolt shell chamber 30 and terminating in a wedge 41. The chamber entering portion 40 of the actuator 38 has a transverse slot 42 and the actuator also has a rearward extension 43 provided with a recess 44 in its upper edge. (See Figs. 3 and 6.)

When the actuator 38 is driven forwardly, its wedge 41 engages the contact portions 36 of the locking arms 32 and tends to wedge them outwardly until restrained by the receiver so that a connection between the bolt shell 28 and the actuator 38 is established driving the bolt shell 28 forwardly into its closed position in which the locking arms 32 are free to swing outwardly into the cam pockets 27. Because the contact portions 36 of the arm 32 are rearwardly of but adjacent to the arm pintles 33, the wedging action on the arms is insufficient to have any appreciable braking action on the movement of the bolt shell 28. The thus positioned locking arms 32 are rendered effective to lock the bolt shell 28 in its closed position by blocking them against being cammed inwardly. I accomplish this result by means of a key 45 having shoulders 46 and extending through the bolt shell slot 31 and the actuator slot 42. The key 45 is slidable relative to the bolt shell 28 into or out of a posi-

tion in which its shoulders 46 underlie the locking arm ledges 37 thereby positively blocking movement of the locking arms 32. The key 45 is also slidable with reference to the actuator 38 since its slot 42 is dimensioned to require predetermined movement of the actuator 38 in either direction before the key 45 is picked up by and moved with it. By this construction, the bolt shell 28 is closed and its locking arms 32 are fully seated in the pockets 27 before the key 45 is operatively positioned and in the unlocking or rearward stroke of the actuator 38, the actuator moves a predetermined distance before the key 45 is picked up to enable the locking arms 32 to be cammed out of their pockets 27. It will be apparent from Fig. 2 that the mutually engageable cam portions 35 and cam pockets 27 are such as to provide for the absorption by the receiver 20 of rearward thrust on the bolt shell 28 with a minimum inward camming action on the locking arms 32. It will be apparent, that, when the firearm is discharged, only a small part of the gas pressure on the head of the bolt shell 28 is transmitted against the key shoulders 46 but preferably as shown in the drawings, the shoulders 46 and the ledges 37 present substantially parallel surfaces, when the bolt shell 28 is locked to the receiver 20, thereby to minimize frictional resistance to the rearward movement of the key 45. (See Fig. 2.)

The bolt shell 28 carries a suitable extractor. While the extractor may be of any desired type, that shown in the drawings is simple in construction and has proved satisfactory in use. I provide the bolt shell 28 with a peripheral groove 47 adjacent its head and having a channel 48 in communication with the face 29. The bolt shell, as may be seen in Fig. 4, has flat surfaced portions 49 in the groove 47 inclined towards each other to receive the resilient clip 50 which is formed integrally with the extractor 51 which extends forwardly in the channel 48 and is exposed in the recessed face 29 to engage with and grip the rim of the cartridge 24 seated in the barrel chamber thereby to pull it therefrom when the bolt moves towards its open position.

As illustrative of means to eject an extracted cartridge or case through the receiver port 25, I have shown (see Fig. 8) a support 52 in the receiver 20 below the path of the bolt 23. On the support is pivotally mounted a U-shaped member 53 of resilient stock disposed to yieldably engage the bolt shell 28 and to enter a slot 54 in its bottom portion thereby to be engaged by an extracted cartridge or case as the bolt 23 moves into its open position to dislodge it from the extractor 51 and eject it through the port 25.

In practice, I provide a firing pin having a rear portion 55 of greater cross sectional area than its front portion 56 thereby to provide an intermediate shoulder 57. The rear part of the actuator 38 has an axial bore 58 to slidably support the pin portion 55, and its front part and the bolt shell 28 each have an axial bore 59 slidably receiving the pin portion 56, and the key 45 has a bore dimensioned to receive the pin and to provide a shoulder 60 engageable by the pin shoulder 57. While the pin portion 55 is slidably connected to the actuator 38 for short movement relative thereto by the transverse pin 61 engageable with the extremities of the recess 62, the shoulder 60 in the key 45 prevents the firing pin from being operatively positioned until the key 45 positively supports the locking arms

32 in the receiver pockets 27. By this construction, the firing pin serves to hold the bolt shell, the key in the actuator together enabling the bolt to be quickly and easily assembled or taken apart.

Before describing the firing mechanism, it is convenient to consider the bolt operating means. While the actuator 38 may be moved forwardly and rearwardly to lock and unlock the bolt shell 28 to the receiver 20 manually or by other means, I have shown it as operated by gas pressure.

To accomplish this, I provide a slide consisting of a pair of members 63 interconnected at their rear ends by an upwardly disposed loop 64 seated in the recess 44 on the actuator extension 43 and including contact shoulders 65 adjacent its lower end. The loop 64 holds the pin 61 in place so that the bolt 23 is held against disassembly until the loop 64 is disconnected therefrom. The members 63 extend forwardly below the barrel 21 but in parallel with its axis and have their front ends interconnected as at 66. The slide part 66 is apertured to receive the rod 67 seated against the downwardly disposed receiver post 68. A spring 69 locked as at 70 to the rod 67 and supported thereby engages the slide part 66 yieldably urging it forwardly into a position in which the bolt 23 is closed.

The stock 22 includes a fore part 71, commonly called the fore stock, and is chambered as at 72 to receive the bolt operating slide and is slotted as at 73 so that a portion of one of the members 63 of the slide is exposed and to it I secure a charging handle 74 by which the bolt 21 may be manually operated against the action of the spring 69. The slot 73 is of sufficient length to accommodate the handle 74 as the bolt 21 reciprocates between its open and closed positions. The handle 74 has a pair of spaced dovetailed lugs 75 (see Fig. 12) and is recessed to receive the lock 76 which has an arm 77 resiliently urging its locking head 78 outwardly adjacent one of the lugs 75 and its operating arm 79 into a position in which its is easily engaged. The portion of the member 63 to which the handle is to be attached has a pair of openings 80 spaced to receive the lugs 75 and including beveled extensions 81 which lock the lugs when slid therein as will be apparent from Figs. 11 and 12. When the handle is locked to the member 63, the locking head 78 blocks one of the openings 80 so that sliding movement of the handle 74 relative to the member 63 is impossible unless the operating arm 79 is pressed to retract the locking head into the handle 74. (See Fig. 2.)

While the bolt 23 may be variously operated, either automatically or manually, I have shown it in Fig. 1 as unlocked by gas pressure. To accomplish this result, I secure a cylinder 82 to the barrel 21 with a port 83 effecting communication between them. Within the cylinder 82 is a piston 84 having one end 85 of reduced diameter and normally seated against one end of the cylinder 82. The other piston end 86 is also of reduced diameter and extends through the sealing plug 87.

At 88, I have shown a tappet which is slidably seated on the exposed end 86 of the piston and is bored to slidably receive the rod 67 and to have predetermined limited movement relative thereto. A spring 89 supported by the rod 67 yieldably maintains the tappet 88 in spaced relation thereto and urges the piston 84 forwardly in its cylinder 82. By this construction, the piston 84 has a relatively short stroke and through the

tappet 88 exerts sufficient power on the slide to carry the actuator 38 rearwardly to unlock the bolt shell 28. Because of the relative movement between the actuator 38 and the key 45, the unlocking of the bolt shell 28 is timed so that the gas pressures in the barrel 21 are safe to employ in ensuring or continuing the movement of the bolt 23 into its open position.

This construction also has the advantage that 10 it provides for ease in assembly or disassembly of a firearm in accordance with my invention. It will be noted that the rear end of the receiver 20 is closed by a threaded cap 90 recessed to receive the buffer spring 91 engageable by the 15 bolt when in its open position. Adjacent to but forwardly of the cap 90, I form the receiver 20 with a recess 92 in its upper part dimensioned to enable the slide loop 64 to be raised out of the recess 44 on the actuator extension 43 thereby 20 to disconnect the bolt 23 from the operating slide.

Because of the tappet connection between the piston 84 and the rod 67, the rod 67 is held sufficiently rigidly to prevent such lifting of the 25 slide until the tappet 88 has been fully seated against the rod 67 and the piston 84 is in contact with the front wall of the cylinder 82. The rod 67 may then be lifted from its seat in the post 68. In order to prevent the tappet 88 from 30 becoming lost, it is slidably pinned to the rod 67 as at 93.

In Fig. 1, I have shown trigger controlled firing mechanism which is well adapted for use in semi-automatic operation of a firearm and which 35 can be readily converted to full automatic operation as shown in Figs. 16-18.

At 94, I have shown a base plate having at its rear end an upright 95 and formed to establish a well 96 slidably receiving the magazine 26 40 and having a groove 97 on its front edge. In accordance with my invention, the firing mechanism is attached to the receiver 20 so that it may be removed from the stock 22 therewith. I accomplish this result by providing the receiver cap 90 with one and preferably two depending arms 98 adapted to receive the upright 95 between them and having a tongue and groove interlock 99. The vertical groove 97 is adapted to receive the receiver post 68 and the groove 97 and post 68 have a tongue and groove interlock 100. The interlocks 99 and 100 present surfaces that are substantially in parallel with the axis of the barrel 21 so that the firing mechanism may be slid forwardly relative to the receiver and connected thereto. As will be apparent from the drawings, the slidable interlock 99 is of sufficiently greater length than the interlock 100 to enable the former to become partially established ahead of the entry of the post 68 into the groove 97.

When the firing mechanism is thus connected to the receiver 20, it is positively locked thereto by means of a bolt 101 extending through the arms 98 of the cap 90 and the upright 95 and the bolt 101 is, in practice, the means locking the receiver and firing mechanism to the stock 22. (See Fig. 5.)

Particularly, when a firearm is to be used for military purposes, it is provided with a hand guard 102 which fits over the barrel 21 forwardly of the receiver 20 and engages the fore stock 71 to which it is connected by a removable clip 103.

In accordance with my invention, I form the hand guard 102 to fit loosely over the barrel 21

and preferably also inlet the fore stock 71 so that the barrel 21 is a loose fit therein. The junction of the receiver 20 and the barrel 21 establishes a shoulder 104 having an arcuate recess 105 and adjacent thereto the barrel has a rearwardly disposed shoulder 106 (see Fig. 13.)

I provide the hand guard 102 with an arcuate lip 107 which enters the recess 105, a resilient catch 108 engageable with the barrel shoulder 106 and a barrel engaging spring element 109 adjacent its front end and preferably a like element 110 is mounted adjacent the front end of the fore stock 71. By this construction, when the hand guard is locked to the fore stock 71, by the clip 103, the spring element or elements are tensioned against the barrel 21. This not only results in a support for the barrel 21 that does not depend on accurate inletting and is not subject to swelling or warping of the wood, but also ensures cooler operation because of the otherwise loose fit of the barrel in the hand guard and forestock.

For maximum convenience, I prefer to use a clip 103 of the type shown in Fig. 15 and made from resilient stock. A loop 111 for a sling (not shown) includes a pair of parallel arms 112 and 113. The arm 112 is pivotally connected to the free end 114 of the clip 103, the other free end of which includes an outward curve 115. I pivotally secure a cam 116, having an operating lever 117, to the arm 113. The cam 116 engages with the curve 115 and as the cam is rocked passed center, the free ends of the clip 103 are drawn together and the cam 116 placed under suitable locking tension. Preferably, the hand guard 102 and the fore stock 71 are recessed to establish a barrel receiving groove 118.

The firing mechanism shown in the drawings consists of a hammer 119 pivotally mounted on the base plate 94 to swing from a position engaging the rear end of the firing pin when the bolt 23 is closed and rocked rearwardly into a cocked position by rearward movement of the bolt travelling into its open position. The forked end 120 of an actuator rod 121 is pivotally connected to the hammer 119 while its free end is slidably supported in a block 122 having a shoulder 123 engageable by the sear 124 adjacent the free end of the rod thereby to hold the hammer 119 in its cocked position. A firing spring 125 supported by the rod 121 engages the forked end thereby to drive the hammer 119 forwardly when the sear is disengaged from its shoulder. A spring 126 anchored to the plate 94 ensures engagement of the sear with its shoulder during operation.

Pivotally connected to the plate 94 is a trigger 127 shown as protected by the trigger guard 128. The trigger 127 has a pocket 129 (see Fig. 16) in which is pivotally mounted a pawl having an arm 130 under the control of a spring 131 yielding urging its other arm 132 forwardly and upwardly. Thus, when the trigger 127 is pulled, the arm 132 engages the free end of the rod 121 and raises it to disengage the sear from its shoulder, but if the trigger is held back, the pawl arm 132 yields and is rocked rearwardly by the rod 121 ensuring the re-locking of its sear during semi-automatic operation of the firearm.

At 133, I have shown a member slidably supported by the block 122 to be shifted laterally relative to the rod 121 into first and second positions in which the member is locked by the detent surfaces 134. The member 133 is dimensioned so that in its first position, upward movement of

the rod 121 is prevented thereby providing a safety while it is recessed as at 135 so that in its second position, the rod 121 may be lifted to release its sear. This type of safety is satisfactory because it is positive, conveniently located, and easily operated. In practice, the member 133 is threaded at one end to receive a nut 136 and extends through the stock 22 so that its extremities are exposed on both sides thereof but countersunk with reference to the surfaces thereof.

The trigger guard 128 is locked at its rear end to the plate 94 by the bolt 137 which also serves to anchor the spring 126 in place while its front end is slidably connected thereto as at 138 and it 15 and the magazine 26 are formed with complementary interlocking portions 139 to hold the magazine securely in place. The trigger guard 128 is sufficiently resilient so that it may be engaged in the zone 140 to enable the interlocking portions to be disengaged thereby providing a safe magazine release.

The firing mechanism just described may be rendered fully automatic as shown in Figs. 16-18. I pivotally mount on the plate 94 an arm 141 disposed to be swung rearwardly to force the pawl arm 132 back out of the path of the rod 121. Mounted on the pivot support for the hammer 119 is a U-shaped member 142 having its closed end presenting a shoulder 143 engageable by the pawl arm 132 when held back by the arm 141 so that the rear end of the member 142 is lifted when the trigger is pulled. Pivotally connected to the member 142 intermediate its ends is a second U-shaped member 144 having its closed end 35 146 rearwardly of the block 122 and below its shoulder 123 and its free ends 145 extending forwardly and upwardly and terminating normally just below the path of the contact shoulders 65 as the bolt 23 reciprocates. When the trigger is 40 now pulled to lift the member 142, the second member 144 is also raised sufficiently so that its free ends 145 are in the path of the contact shoulders 65 to be engaged thereby to rock the second member to lift its closed end 146 to release the sear so that so long as the trigger is held back, the firearm functions automatically.

From the foregoing, it will be apparent that firearms in accordance with my invention have many important features and advantages. The 50 most important of these relate to the bolt as they ensure simplicity of construction, ease of operation, and a positive lock of the bolt in its closed position that is easily established and easily released regardless of the bolt operating means 55 used in conjunction therewith.

What I therefore claim and desire to secure by Letters Patent is:

1. In a firearm, a barrel having a chamber, a receiver having an ejection port and a cam pocket, and a bolt in said receiver reciprocable between a closed position in which it seats a cartridge in said chamber and an open position rearwardly of said port, said bolt comprising a shell having at one end a cartridge engaging face, an actuator slidably with reference to said shell, and a locking arm pivotally connected to said shell and including an outer cam portion substantially complementary in size and shape to said pocket and located to swing outwardly into said pocket when the bolt shell is in its closed position or inwardly into a position in which said bolt shell is free to reciprocate, said actuator engaging said arm and tending to wedge it outwardly, and a key including a shoulder and being slidable with

reference to said shell into and out of a position in which its shoulder is engageable by the free end of said arm to lock said arm in said pocket, said key also being slideable with reference to said actuator to provide predetermined movement in either direction of the latter before the former is moved.

2. In a firearm, a barrel having a chamber, a receiver having an ejection port and a pair of transversely alined cam pockets, and a bolt in said receiver reciprocable between a closed cartridge seating position and an open position rearwardly of said port, said bolt comprising a shell, locking arms pivotally connected to said shell to swing from an inoperative position in which said shell is free to reciprocate into an outer position and being located so that they may enter said pockets when the bolt shell is in its closed position, an actuator movable forwardly relative to said shell to engage said arms thereby to drive said bolt shell forwardly and to wedge them apart when said bolt shell is closed and means slideable relative to said bolt shell to block inward movement of said arms, said means being slideably connected to said actuator to move into and out of arm blocking position in lagging relation to said actuator.

3. In a firearm, a barrel having a chamber, a receiver having an ejection port and a pair of transversely alined cam pockets, and a bolt in said receiver reciprocable between a closed position in which it seats a cartridge in said chamber and an open position rearwardly of said port, said bolt comprising a shell having at one end a cartridge engaging face, an axial chamber opening through its other end, and a transverse slot intersecting said chamber, and a pair of locking arms, a pivotal connection between each arm and said shell, each of said arms including an outer cam portion substantially complementary in size and shape to said pockets, an inner contact portion, and a ledge spaced rearwardly thereof, said arms being housed in opposite ends of said slot to have an inoperative position therein in which said bolt shell is free to reciprocate and being located so that when said bolt shell is in its closed position each of said arms may be pivoted outwardly and into one of said receiver pockets to lock said bolt shell against rearward movement, an actuator including a portion slideably extending into said bolt shell chamber and having a transverse slot and a wedge engageable with said contact portions thereby to urge said arms outwardly, and a key interconnecting said bolt shell and said actuator through their transverse slots, said key including shoulders and being slideable with reference to said bolt shell into and out of position in which said shoulders are engageable by said ledges to lock said arms in their operative position, said key also being slideable with reference to said actuator thereby to provide predetermined movement in either direction of the latter before the former is moved.

4. The firearm of claim 3 in which the mutually contacting surfaces of the shoulders and the ledges are substantially in parallel when the locking arms are in the receiver pockets.

5. The firearm of claim 3 in which each pivotal connection consists of a tapered pintle integral with each arm and a tapered pintle receiving bore intersecting the shell slot ends adjacent their front extremities.

6. In a firearm, a barrel having a chamber,

a receiver having a port and a pair of transversely alined cam pockets, a bolt in said receiver reciprocable between a closed position in which it seats a cartridge in said chamber and an open position rearwardly of said port, and a firing pin having its front portion of lesser cross sectional area than its rear portion and establishing a shoulder, said bolt comprising a shell having at one end a cartridge engaging face, an axial chamber opening through its other end, and a transverse slot intersecting said chamber, and a pair of locking arms, each of said arms including an outer cam portion substantially complementary in size and shape to said pockets, an inner wedge, and a ledge spaced rearwardly thereof, said arms being pivotally connected to said bolt shell and housed in opposite ends of said slot to have an inoperative position therein in which said bolt shell is free to reciprocate and being located so that when said bolt shell is in its closed position each of said arms may be pivoted outwardly and into one of said pockets to lock said bolt shell, an actuator including a portion extending into said bolt shell chamber and having a transverse slot and a wedge contacting surface, and a key interconnecting said bolt shell and said actuator through their transverse slots, said key including shoulders and being slideable with reference to said bolt shell into and out of a position in which said shoulders are engageable by said ledges to lock said arms in their operative position, said key also being slideable with reference to said actuator thereby to provide predetermined movement of the latter before the former is moved, said shell, said actuator having bores to slideably receive the front and rear portions of said firing pin respectively, means connecting said pin to said actuator for limited sliding movement relative thereto, and said key having a pin passage therethrough dimensioned to receive said pin and establishing a seat engageable by its shoulder so that said actuator and said key are connected to said shell and said firing pin is prevented from becoming operative until said locking arms are operatively positioned.

7. In a firearm, a barrel having a chamber, a receiver having an ejection port and a pocket, and a bolt in said receiver reciprocable between a closed position in which it seats a cartridge in said chamber and an open position rearwardly of said port, said bolt comprising a shell having at one end a cartridge engaging face, an actuator slideable with reference to said shell, a locking arm, a pivot connecting said arm to said shell and including a portion to enter said pocket to lock the bolt against rearward movement and located to swing outwardly into said pocket when the bolt shell is in its closed position or inwardly into a position in which said bolt shell is free to reciprocate, said arm and said pocket also including mutually engageable cam portions tending to swing said arm inwardly when said bolt shell is urged rearwardly, said actuator engaging said arm rearwardly of but adjacent to said pivot to drive said shell forwardly and tending to wedge said arm outwardly, and a key including a shoulder and being slideable with reference to said shell into and out of a position in which its shoulder is engageable by the free end of said arm to lock said arm in said pocket against being cammed inwardly, said key also being slideable with reference to said actuator and being engaged thereby on predetermined movement in either direction of the latter before the former

is moved into or out of its locking position thereby to provide means to enable force applied to said bolt urging it towards its open position to be delayed before it causes said arm to be cammed inwardly.

8. In a firearm, a barrel having a chamber, a receiver having an ejection port and a cam pocket, and a bolt in said receiver reciprocable between a closed position in which it seats a cartridge in said chamber and an open position rearwardly of said port, said bolt comprising a shell having at one end a cartridge engaging face, an actuator slidable with reference to said shell, a locking arm, a pivot connecting said arm to said shell, said arm including an outer cam portion to enter said pocket and being located to swing outwardly into said pocket when the bolt shell is in its closed position or inwardly into a position in which said bolt shell is free to reciprocate, said actuator engaging said arm rearwardly of but adjacent to said pivot to drive said shell forwardly and tending to wedge said arm outwardly, and a key including a shoulder and being slidable with reference to said shell into and out of a position in which its shoulder is engageable by the free end of said arm to lock said arm in said pocket against being cammed inwardly, said key also being slidable with reference to said actuator and being engaged and moved thereby on predetermined movement in either direction of the actuator.

9. In a firearm, a barrel having a chamber, a receiver having an ejection port and a pocket, and a bolt in said receiver reciprocable between a closed position in which it seats a cartridge in said chamber and an open position rearwardly of said port, said bolt comprising a shell having at one end a cartridge engaging face, an actuator slidable with reference to said shell, a locking arm pivotally connected to said shell and including an outer portion to enter said pocket to lock the bolt against rearward movement and located to swing outwardly into said pocket when the bolt shell is in its closed position or inwardly into a position in which said bolt shell is free to reciprocate, said arm and said pocket also including mutually engageable cam portions tending to swing said arm inwardly when said bolt shell is urged rearwardly, said actuator engaging said arm and tending to wedge it outwardly and a key including a shoulder and being slidable with reference to said shell into and out of a position in which its shoulder is engageable by

the free end of said arm to lock said arm in said pocket against being cammed inwardly, said key also being slidable with reference to said actuator to provide predetermined movement in either direction of the latter before the former is moved.

10. In a firearm, a barrel having a chamber, a receiver having an ejection port and a pair of transversely aligned cam pockets, and a bolt in said receiver reciprocable between a closed cartridge seating position and an open position rearwardly of said port, said bolt comprising a shell, locking arms pivotally connected to said shell to swing from an inoperative position in which said shell is free to reciprocate into an outer position and being located so that they may enter said pockets when the bolt shell is in its closed position, bolt actuating means including a forwardly and rearwardly reciprocable part, an actuator part having limited forward and rearward movement relative to said shell and in its forward movement engaging said arms thereby to drive said bolt shell forwardly and to wedge said arms apart when said bolt shell is closed, and means to block said arms against inward movement when said arms are in their blocking position, said means having limited forward and rearward movement relative to said shell and to one of said parts to lag behind said last named part on rearward movement thereof.

HOWARD R. CLARKE.
